ROASTING AND SMELTING FURNACE

Hans William Jaeger, Seattle, Wash., assignor
of one-half to Fred B. Dawley, Seattle, Wash.

Application March 15, 1937, Serial No. 130,811

3 Claims. (Cl. 266—10)

This invention relates to roasting and smelting furnaces of the reverberatory type and the primary object of this invention is to provide a furnace of this nature in which the roasting and smelting of ores is carried out in one continuous process.

Another object of the invention is to provide a continuous process roasting and smelting furnace of this type which is adapted to be constructed in comparatively small sizes thus making said furnaces available for use in smaller mining operations and making it especially desirable for use in mines which have poor transportation facilities and which are located at great distances from smelters.

Another object of the invention is to provide a continuous process roasting and smelting furnace having three separately constructed sections providing an upper roasting chamber, a lower smelting chamber and a temperature control chamber positioned between the roasting and smelting chambers.

Another object of the invention is to provide a continuous process reverberatory roasting and smelting furnace which is adapted for either low grade or complex ores, which is simple in construction and efficient in operation and which makes possible a substantial saving in transportation and smelter costs.

Another object of this invention is to provide a combined roasting and smelting furnace of this nature having means which collects and retains substantially all dust and substantially all zinc and arsenic and like substances which are volatilized during the smelting process and which would otherwise pass out through the stack.

Another object is to provide a continuous process roasting and smelting furnace which uses less flux than is ordinarily used in the smelting of ores and which does not require any flux at all in the smelting of some ores.

Other objects are to provide a continuous process roasting and smelting furnace which saves in fuel due to the fact that it employs a hydrocarbon burner, which saves in the time of roasting and smelting, as the furnace can be tapped at more frequent intervals than the ordinary smelter furnace, which saves in the cost of labor required in connection with the roasting and smelting of ore and which obtains a higher percentage of recovery from the ores due to the maintaining of a more complete and even fluidity which results in a cleaner and more complete separation.

Other and more specific objects of the invention will be apparent from the following description taken in connection with the accompanying drawings.

In the drawings Fig. 1 is a longitudinal vertical section of a continuous process ore roaster

and smelter constructed in accordance with this invention.

Fig. 2 is a transverse vertical section of the same, taken substantially on a broken line 2—2 of Fig. 1.

Fig. 3 is a horizontal section substantially on broken line 3—3 of Fig. 1.

Fig. 4 is a diagrammatic view of one form of driving means that may be used with the invention.

Like reference numerals designate like parts throughout the several views.

The continuous process roasting and smelting furnace shown in the drawings is made up of a lower ore smelting section 10, a medial temperature adjusting section 11, and an upper ore roasting section 12. The lower section 10 comprises a smelting chamber 13 surrounded by walls 14 of heat resistant material, as firebrick, and having a floor portion 15 preferably of silica sand. The entire structure may rest on a base 16 of concrete. Suitable openings 17 and 18 may be provided in the walls 14 of the lower section for tapping the same to draw off the slag and matte.

A hydrocarbon burner 19 extends into one end or into any other suitable portion of the smelting chamber 13 above the level at which material will normally be maintained therein. The top of the smelting chamber 13 is formed by arches 20 of heat resistant masonry.

These arches 20 have upwardly protruding portions 21 which interfit telescopically with downwardly protruding portions 22 of the medial section 11 and form expansion joints between these two furnace sections. An upright passageway 23 connects the end portion of the smelting chamber remote from the hydrocarbon burner with a horizontal temperature adjusting chamber or passageway 24 in the medial section 11.

An inclined ore inlet passageway 25 communicatively connects the smelting chamber 13 with the medial section 11 near the end at which the hydrocarbon burner 19 is positioned. The inclined passageway 25 allows roasted ore to pass from the upper chambers into the smelting chamber 13.

The medial temperature adjusting section 11 and upper smelting section 12 are each supported on transverse metal beams 26 and said beams 26 are supported by a steel frame work 27 provided on the exterior of the roasting and smelting furnace. This means of support makes it possible to construct the three sections 10, 11 and 12 independently of each other and to provide successful expansion joints therebetween.

A roasting chamber 28 is provided in the upper furnace section 12 and an endless driven ore conveyor is provided in said roasting chamber. This endless driven ore conveyor comprises a plurality 60

of links 29 operable on sprocket wheels 30. The sprocket wheels 30 are mounted on transverse shafts 31 and 32 which are journaled in bearings 33 positioned in the walls or external to the walls 5 of the upper furnace section 12. Preferably both of the shafts 31 and 32 are driven as by link belts 34 operating on sprocket wheel means 35 on said shafts and connected with sprocket pinion means 36 of transmission 37. The sprocket pinion means 36 is connected by worm wheel 38, worm 39, bevel gears 40, sprocket wheel 41, link belt 42 with a driving means as a motor 43 which preferably provides at least three different driving speeds. The above described driving means provides for driving the ore conveyor at very slow 10 speed and for applying the driving power at both ends of the same.

When necessary, especially in connection with 20 relatively long conveyors, driving force may be applied at one or more locations between the two ends.

The links 29 of the conveyor are preferably 25 in the form of specially constructed flat plates articulated together and extending substantially across the roasting chamber to form an endless traveling apron on which the ore may rest during 30 the roasting process. These plate like link members 29 preferably rest upon track members 45 on the walls of the furnace as shown in Fig. 2. Preferably the shafts 31 and 32 are hollow, as shown.

An ore hopper 46 is positioned to deliver ore 35 onto one end of the ore conveyor. A driven rotary feed valve 47 may be provided in connection with the hopper 46 to insure an even feed of ore onto the ore conveyor and to prevent the escape of smoke and by-products of combustion through the hopper.

A plurality of fixedly mounted rabble arms 48 40 extend crosswise of the roasting chamber 28 above the ore conveyor and rabble blades 49 on said rabble arms extend downwardly into the path of the ore on the ore conveyor in suitable 45 positions to stir and agitate the ore on the conveyor as it passes the location of said rabble arms. The rabble arms are of tubular construction providing for a circulation of air there-through to keep said arms from becoming overheated.

The movement of the conveyor is timed so that 50 the ore will be completely roasted as it is carried from the point of inlet to the discharge end of the conveyor. When the ore is discharged from the discharge end of the conveyor it falls through 55 a vertical passageway 50 onto an inclined metal plate or apron 51 which directs said roasted ore downwardly through the inclined passageway 25 into the smelting chamber 13. The apron 51 is of heat resistant material, preferably of cast iron and the major portion of the space beneath 60 said apron 51 is open so as to afford a free circulation of air in contact with said apron for the purpose of cooling said apron. A wedge shaped deflector member 52 of metal is provided 65 to protect the masonry from contact with the falling ores.

The medial furnace section 11 is provided with a bottom portion 53, upright walls 54 and an arched top portion 55. An air space 56 is provided 70 between the arched top portion 55 of the medial furnace section and the bottom 57 of the upper furnace section. The upper furnace section has an arched top wall portion 58 above which is a flat top portion 59.

Positioned just in front of the ore inlet hopper

46 is a transverse passageway 60 for by-products of combustion. The walls enclosing the passageway 60 preferably extend a short distance above the top of the furnace, Fig. 1, and said passageway 60 communicates with one or 5 more dust chambers 61, Fig. 2, at one side of the furnace. The wall 62, Fig. 1, between the passageway 60 and the hopper 46 extends downwardly to a location near the endless traveling ore conveyor leaving just enough clearance for 10 the ore on the conveyor to pass under the bottom edge of said wall and forming a baffle plate helping to prevent hot gases, smoke and by-products of combustion from passing outwardly through and around the hopper. 15

The dust chambers 61 are each provided with a convergent lower portion 63 through which dust and solid by-products of combustion may pass downwardly to be disposed of in any suitable manner while smoke and gases which can 20 not be caught in these dust chambers pass outwardly and up through a stack 64. To direct the heated by-products of combustion downwardly in the dust chambers 61 and to assist in the removal, from the by-products of the smelting and roasting furnace, of dust and gases which may carry values or which may be objectionable if released in the atmosphere, I preferably provide in the top portion of each dust chamber a deflector wall 66 which extends downwardly into the dust chamber. Also I provide 25 means for spraying water into each dust chamber. This spray means may consist of water conduits 65 having perforations positioned to direct very finely divided sprays of water across 30 the passageways 72 through which the by-products of combustion are traveling in a downward direction. Also I make the passageway 72, through which the by-products travel downwardly, of smaller size than the passageways 73 35 40 through which the by-products travel upwardly. This accelerates the downward velocity of the by-products and helps to deposit the solid particles in the dust chamber. The water is sprayed under high pressure. This spray is very 45 finely divided and thoroughly washes the gases which later escape up the stack. Also the water spray helps to separate the solid matter from the gases by wetting the solid particles and causing 50 them to adhere together so that they are more 55 liable to drop into the bottom portions of the dust chambers. Any suitable drain means is provided in the bottom portions of the dust chambers to prevent the accumulation of water therein. This dust chamber and spray 60 system forms an important part of this invention as it provides an efficient means for the recovery of values which might otherwise escape through the smoke stack and further provides means for cleaning the smoke and by-products of combustion of objectionable solid matter and gases. More than two dust chambers 61 may be provided if desired. 65

I find that more heat than is required for the roasting of the ores will often be traveling upwardly through the passageways that lead from the smelting chamber 13 to the roasting chamber 28 and for the purpose of regulating this heat and utilizing said heat to the best advantage I provide in the end of the medial section 11 two 70 openings 66 and 67. The opening 66 is connected with a conduit 68 which may lead to any suitable location where heat which is taken off may be utilized as for instance to boiler rooms. A damper 69 is provided in the conduit 68 and it 75

will be understood that sufficient draft or suction is present in the conduit 68 to cause a portion of the heated gases to pass outwardly through this conduit 68 when the damper 69 is 5 open or partly open. The opening 67 opens to the atmosphere and functions like a check draft for admitting cold air to the heated by-products of combustion, said opening 67 having a damper 70 by which it may be opened and closed.

10 In the operation of this continuous process roasting and smelting furnace, ore to be roasted and smelted is fed from the hopper onto the ore conveyor and combustion is provided in the smelting chamber 13. As the ore is carried toward 15 the discharge end of the conveyor the heated by-products of combustion from the smelting chamber 13, which have traveled in a generally upward direction through passageways 23, 24 and 50, pass over said ore and roast it to the desired 20 extent. The ore is spread out in a relatively thin layer on the ore conveyor and is stirred by the rabble blades as it progresses thus giving the heated gases even access to all of said ore and roasting the same thoroughly in a short period 25 of time. The speed of the ore conveyor may be varied to vary the roasting time for different ores and in proportion to different degrees of heat. The thoroughly roasted ores discharge 30 into the reverberatory smelting chamber 13 where they are reduced to a molten or fluid state providing for a gravity separation of the gangues from the metals, thus permitting first the slag and then the matte to be tapped off in the usual manner.

35 From the foregoing description it will be seen that I have provided a continuous process roasting and smelting furnace which can be constructed in small sizes at a cost which makes possible its installation at smaller mines; that 40 I have provided a continuous process roasting and smelting furnace in which the ores pass directly from a roasting chamber into a smelting chamber and in which the excess heat from the smelting chamber is utilized for roasting the ores 45 thus reducing heat losses and costs of ore handling to a minimum. Also by providing the temperature control chamber between the roasting and smelting chambers I have provided an efficient means for controlling the temperature in 50 the roasting chamber. The dust chamber further provides a simple and efficient means for recovering values and removing objectionable gases which would otherwise escape through the stack.

55 The foregoing description and accompanying drawings clearly show a preferred embodiment of my invention but it will be understood that this disclosure is merely illustrative and that such changes may be made as are within the 60 spirit and scope of the following claims.

I claim:

1. In a continuous process roasting and smelting furnace; a smelting chamber; a roasting chamber positioned directly above said smelting chamber; movable ore supporting means in said roasting chamber positioned to discharge roasted ore from one end portion of said roasting chamber downwardly into a corresponding end portion of said smelting chamber; and a temperature 65 control chamber positioned between said smelting chamber and said roasting chamber and communicatively connected with the ore discharge end of said roasting chamber and the opposite end of said smelting chamber and providing a

passageway through which heated products of combustion from said smelting chamber may pass to said roasting chamber; hot gas take off means connected with said temperature control chamber; and cold air inlet means connected with said temperature control chamber, said hot gas take off means and cold air inlet means providing for the control of the temperature of the gases passing through said temperature control chamber to said roasting chamber. 10

2. In a continuous process roasting and smelting furnace, a smelting chamber; a hydrocarbon burner in said smelting chamber; a roasting chamber positioned directly above said smelting chamber; a temperature control chamber positioned between said roasting chamber and said smelting chamber communicatively connected at one end by a hot gas passageway with said roasting chamber and at the other end by a hot gas passageway with said smelting chamber providing conduit means through which hot gases may pass from said smelting chamber to said roasting chamber, said three chambers being substantially horizontal and said hot gas passageways extending in generally upright directions 25 between said chambers; an endless traveling ore conveyor mounted in said roasting chamber positioned to discharge ore downwardly through the hot gas passageway which connects said roasting chamber and said temperature control chamber 30 and across the path of the ascending hot gases; means forming a conduit between said temperature control chamber and said smelting chamber substantially at the bottom of the hot gas passageway connecting the roasting chamber with 35 the temperature control chamber through which said ore may pass downwardly into said smelting chamber; temperature control means connected with said temperature control chamber providing for the control of the temperature of gases 40 passing through said temperature control chamber to said roasting chamber; and means admitting ore into the intake end of said roasting chamber onto said traveling conveyor.

3. In a continuous process roasting and smelting furnace, a relatively long horizontal smelting chamber; heat generating means in said smelting chamber; a temperature control chamber positioned directly above said smelting chamber substantially parallel therewith; passageway 50 means for heated gases connecting one end portion of said temperature control chamber with the adjacent end portion of said smelting chamber; an inclined deflector plate positioned at the other end portion of said temperature control chamber; passageway means for material positioned at the lower edge of said inclined plate communicating with said smelting chamber; a roasting chamber positioned directly above said temperature control chamber substantially parallel 55 therewith; passageway means communicatively connecting the end portion of said temperature control chamber adjacent said inclined plate with the adjacent end portion of said roasting chamber; ore inlet means positioned at the other end portion of said roasting chamber; ore moving means in said roasting chamber adapted to move ore from said ore inlet through said roasting chamber and discharge the ore onto said inclined plate; and temperature control 60 means connected with said temperature control chamber. 65

HANS WILLIAM JAEGER.
